US0D1007326S

(12) **United States Design Patent** (10) **Patent No.:** **US D1,007,326 S**
(45) **Date of Patent:** **** Dec. 12, 2023**

(54) **PACKAGING BAG**

(71) Applicant: **FLAT SYSTEM S.R.L.**,
Camposampiero (IT)

(72) Inventors: **Ronnie Pallaro**, Padua (IT); **Marco Zanchin**, Padua (IT); **Roberto Spagnolo**, Padua (IT)

(73) Assignee: **FLAT SYSTEM S.R.L.**,
Camposampiero (IT)

(**) Term: **15 Years**

(21) Appl. No.: **35/513,629**

(22) Filed: **Jan. 28, 2022**

(80) **Hague Agreement Data**

Int. Filing Date: **Jan. 28, 2022**

Int. Reg. No.: **DM/218758**

Int. Reg. Date: **Jan. 28, 2022**

Int. Reg. Pub. Date: **Feb. 11, 2022**

(30) **Foreign Application Priority Data**

Jul. 30, 2021 (IT) 402021000002030

(51) **LOC (14) Cl.** **09-05**

(52) **U.S. Cl.**

USPC **D9/703**

(58) **Field of Classification Search**

USPC D9/455, 456, 499, 414, 432, 433,
